M. S. ROSENFELD,
PROCESS OF REMOVING SURPLUS POWDER FROM SURFACES.
APPLICATION FILED JUNE 12, 1919.
1,331,582.

Patented Feb. 24, 1920.

UNITED STATES PATENT OFFICE.

MAURICE S. ROSENFIELD, OF NEWARK, NEW JERSEY, ASSIGNOR TO DECALMO MACHINE COMPANY, INC., A CORPORATION OF DELAWARE.

PROCESS OF REMOVING SURPLUS POWDER FROM SURFACES.

1,331,582.

Specification of Letters Patent. Patented Feb. 24, 1920.

Application filed June 12, 1919. Serial No. 303,684.

To all whom it may concern:

Be it known that I, MAURICE S. ROSENFIELD, a citizen of the United States, residing in Newark, in the county of Essex, in the State of New Jersey, have invented certain new and useful Improvements in Processes of Removing Surplus Powder from Surfaces, of which the following is a specification.

10 The present invention relates to a process of removing surplus powder from surfaces, and more particularly the invention relates to a process of removing surplus powder from the transfer tape upon which decal-

15 comanias are printed.

Decalcomanias or transfer pictures are commonly printed upon waxed paper, the wax serving to hold the decalcomania on the paper, so that it can be removed there-
20 from by the application of heat and pres-
sure to the back of the paper when the de-
calcomania is transferred to the textile or
other goods it is designed to mark. The
25 decalcomania or transfer picture is usually
composed of several ingredients in super-
posed layers, one of which is the coloring
matter constituting the body of the de-
calcomania. This coloring matter is often
30 applied in a powdered form, such as bronze
or gold dust and the like. Hereinafter, for
the sake of convenience, the coloring matter
will be referred to as a bronze powder, al-
though the invention is not limited to the
35 removal of such powder from surfaces. In-
asmuch as the bronze is applied to the trans-
fer tape in a powdered state, it is not
printed or impressed upon the tape in the
form of a design, but is dusted on the tape
40 loosely and is caught and held by the tacky
surface of a design previously printed upon
the tape. Such is the nature of the bronze
powder and the wax with which the surface
of the transfer tape is coated that not only
45 does the bronze powder adhere to the tacky
design, but it also adheres so closely to the
waxed surface of the transfer tape that it
cannot be shaken therefrom, but must be
positively removed. If this surplus bronze
50 powder adhering to the waxed surface of
the transfer tape and surrounding each de-
calcomania or transfer picture is not re-
moved from the transfer tape, it is trans-
ferred to the goods to be marked by the de-
55 calcomania when the wax is melted to re-
lease the decalcomania from the transfer

tape. The surplus bronze powder on the goods is detrimental to the appearance of the decalcomania and renders the use of a decalcomania made by the method above described uncommercial. The object of the 60 present invention is to produce a process of removing the surplus bronze powder from the waxed surface of the transfer tape upon which decalcomanias are printed; but it is to be understood that the invention is not to 65 be limited to this purpose, since in its broader aspect it is applicable to the removal of any kind of powder from waxed or un-
waxed surfaces.

The decalcomanias or transfer pictures 70 are conveniently printed or impressed at uniform intervals upon a strip or tape of waxed paper. In building up the decal-
comanias on the transfer tape, there is first
printed a design composed of some tacky 75 substance. Before this substance is dry,
the transfer tape is sprinkled thickly with
the coloring matter, such as the bronze
powder or the like. When the tacky sub-
stance is dry, causing the bronze powder 80 immediately in contact with it to adhere
firmly thereto, the surplus bronze powder
upon the design and that upon the waxed
surface of the transfer tape is removed.
The process of removing the surplus bronze 85 powder from the waxed surface of the trans-
fer tape and from the design constituting
the decalcomania comprises bringing the
bronze powder covered surface of the trans-
fer tape in contact with a powder removing 90 surface and then, without rubbing the two
surfaces together, separating them. The
surplus and loose bronze powder upon the
transfer tape adheres to the powder re-
moving surface and thus the surplus powder 95 is positively removed from the transfer tape.
The powder removing surface is coated with
a sticky substance to facilitate the removal
of the powder from the transfer tape. Care
must be taken that the action is that of daub-
ing or pressing the powder remover against 100
the transfer tape and, without rubbing, sep-
arating the two surfaces by a pulling apart
or lifting action. This is made necessary
by the fact that if a substance is rubbed 105
over the bronze powder covered surface of
the waxed paper, the rubbing causes some of
the bronze powder to strike into the wax
coating of the paper. The powder removing
surface or powder remover is preferably 110

made of some yielding material somewhat softer than the wax, so that when it is pressed upon the transfer tape the bronze powder is not driven into the wax. The 5 powder remover may be of any form answering the purpose, but when the operation of removing the powder is performed mechanically it is preferably made of felt or of a mixture of gelatin and molasses in the form of a roll. Inasmuch as there are usually several layers of surplus bronze powder upon the transfer tape, a pressing and lifting contact between the powder remover and the transfer tape is 10 repeated as often as there are layers of powder upon the tape. Where the operation of removing the powder is performed mechanically, there are provided as many rolls as there are layers of surplus bronze 15 powder upon the transfer tape. This seldom or never exceeds three or, at most, four layers.

In the drawings illustrating an apparatus by which the process of removing the 20 surplus bronze powder from wax coated transfer tapes may be practised, there is provided a series of powder removing rolls, 1, 2, 3 and 4. These rolls are mounted on pins and are rotated at a uniform rate of speed. 25 The peripheral surface of each roll is supplied with a film of some moist and sticky substance, such as gum-arabic, from a feed block 5 composed of felt. Each feed block is saturated with the gum-arabic and occupies 30 the lower end of a water cup 6. The water for keeping the gum-arabic in the block of felt moist is fed to the water cup by a wick 7 depending from a reservoir 8, from which the wick draws the water, drop 35 by drop, by capillary attraction. The blocks of gum-saturated felt 5 are thus kept moist as the water seeps or percolates through them and carries with it some of the gum-arabic which coats the peripheral 40 surface of the roll with a coating of moist and sticky gum. When the transfer tape 9 is brought into contact with the powder removing rolls, the first roll, of course, removes the greater quantity of powder, and 45 each of the remaining rolls removes a decreasing amount, the fourth roll usually removing little or no powder. Each roll is provided with a cleaning block 10, which keeps the surface of the rolls fresh and 50 clean.

After the surplus bronze powder has been thus thoroughly removed from the waxed surface of the transfer tape and the loose bronze powder also removed from the design, the transfer tape is then brought into contact with a roll 11 moistened with water only, which washes the transfer tape. The transfer tape is then passed under a polishing roll 12, which rotates at a higher rate 60 of speed than the other rolls and thus serves

to harden and polish the surface of the bronze powder adhering firmly to the tacky substance constituting the decalcomania design.

The transfer tape 9 is fed through the 70 apparatus from a supply reel 13 to a take-up reel 14. The linear rate of feed of the transfer tape is equal to the peripheral speed of the powder removing rolls, so that there will be no rubbing action between the 75 rolls and the tape, but rather the contact between the rolls and the tape will be a pressing together of the two surfaces and a lifting apart. The action of the powder removing rolls upon the transfer tape is thus 80 a duplication of the manual act of pressing a piece of felt upon the tape and then carefully lifting it therefrom. The transfer tape is pressed into contact or engagement with the powder removing rolls by a series 85 of pressure rolls 15, each of these rolls being flanged so as to properly guide the transfer tape.

It has been found by experiment that if a piece of felt or other yielding surface 90 coated with a sticky substance is rubbed over a bronze powder covered transfer tape, much of the bronze powder is struck into the wax coating of the transfer tape so that when the tape is heated to melt the wax 95 to release the decalcomania, the bronze powder which has been driven into the wax is then released by the melted wax and deposited upon the goods to which the decalcomania is applied. Where, however, the 100 piece of felt or other yielding surface coated with the stick substance is carefully pressed upon the transfer tape, then lifted off without rubbing, and the operation repeated as many times as there are separate 105 layers of powder upon the tape, the bronze powder is effectively removed and is not driven into the wax. The fact that when the transfer tape is passed through the apparatus in contact with the powder removing rolls and is afterward applied to the goods no surplus powder is deposited on the goods proves that the action between the powder removing rolls and the transfer 110 tape is not a rubbing action.

It is to be understood that the form of apparatus illustrated in the drawings for performing the process of removing surplus powder from surfaces is only one of many forms adapted for this purpose. The 115 essential feature to be observed in the practice of the process and in the construction of apparatus for performing it mechanically is that the powder removing surface shall not be rubbed against the bronze powder covered surface of the waxed paper where the latter is the kind of surface from which the surplus powder is to be removed. In the apparatus shown in the drawings, the powder removing surfaces are the periph- 120 125 130 135

eral surfaces of rolls, rolls being chosen for the sake of economy and mechanical convenience. It will be understood, however, that various other mechanical constructions 5 are adapted for the same purpose.

An apparatus suitable for carrying out the herein described process is described and claimed in application Serial No. 303,685; and a transfer tape is disclosed and claimed 10 in application Serial No. 303,683 both of even date herewith.

Having thus described the invention, what is claimed as new is:—

1. The process of removing surplus powder from surfaces, which comprises bringing 15 a powder removing surface covered with a sticky substance in contact with a powder covered surface and separating it therefrom without a rubbing movement thereon.
2. The process of removing surplus powder from surfaces, which comprises subjecting 20 a powder covered surface to the sequential action of a series of powder removing surfaces each of which contacts with the powder covered surface without rubbing it, then washing the surface from which the powder has been removed and finally polishing it.
3. The process of removing powder from 25 surfaces, which comprises subjecting a powder covered surface to a series of powder removing surfaces each of which comes in contact with the powder covered surface sequentially and separating the powder cov-

ered surface from the powder removing surfaces without a rubbing movement between them. 35

4. The process of removing powder from surfaces, which comprises pressing a powder removing surface covered with a sticky substance 40 upon a powder covered surface and removing it therefrom without a rubbing movement.

5. The process of removing bronze powder from a waxed surface, which comprises 45 pressing a powder removing surface covered with a sticky substance against the powder covered waxed surface and lifting it therefrom without rubbing the waxed surface.

6. The process of removing bronze powder 50 from a waxed surface, which comprises bringing a powder removing surface coated with a sticky substance and a waxed surface covered with bronze powder into contact, separating them without a rubbing movement 55 between them, washing the waxed surface and then polishing it.

7. The process of removing bronze powder from a waxed surface, which comprises 60 bringing a powder removing surface coated with a sticky substance into contact with a waxed surface covered with bronze powder, separating the two without a rubbing movement between them and repeating the operation until all the bronze powder is removed 65 from the waxed surface.

MAURICE S. ROSENFELD.
